ELECTRIC SWITCH.

Application filed February 19, 1926, Serial No. 89,497, and in Switzerland March 12, 1925.

This invention relates to an electric switch in which the making and the breaking of an electric circuit is produced brusquely regardless of the speed of motion of the control means acting on the switch.

The switch is applicable to all electric installations where it is important to prevent sparking on making and breaking of a circuit. However, this device is particularly adapted to be applied to electrical apparatuses where a contact or contacts are automatically controlled by a control means having a slow, or a slow periodic movement.

Further objects of this invention are to simplify the structure, increase the efficiency and decrease the cost of production of devices of this character.

The accompanying drawings show by way of example one complete operative embodiment of this invention.

The single figure of drawing is a vertical elevation in diagrammatic form of applicant's invention.

In the form shown in the drawing the switch controls the exciting circuit of an electro-magnet having an armature, which winds the drive spring of a time-piece.

Referring to the figure of drawing two coils 1 of the electro-magnet are placed in a circuit 2 supplied from a battery 3. This circuit is opened and closed periodically by means of a spring contact 4. The electro-magnet comprises an armature 5 pivoted at 6 and subjected to the action of a spring 7 tending to rock it clockwise. At the free end of the armature is a drive pawl 8 the end of which engages in the teeth of a ratchet wheel 9 acting on the drive spring of a time-piece. This type of mechanism being well known, it is sufficient to point out that the pawl 8 turns the ratchet wheel 9 according as the armature 5 is drawn away from the cores 1' of the electro-magnet under the action of the spring 7. Each time that the armature 5 is attracted by the cores 1', the drive pawl 8 moves backward on the teeth of the ratchet wheel and its end passes over two or three ratchet wheel teeth before taking up its position behind a tooth. During this operation of the pawl 8 the ratchet wheel 9 is held from movement by means of a detent of any desired form (not shown in the drawing), while the spring 7 is tensioned anew.

The switch is controlled by the armature 5, the movement of which is rapid when it is attracted by the cores 1' of the electro-magnet, and which is slow when it is drawn away from the cores of the magnet. For effecting this control the armature 5 at its free end carries a spring 10 and two lateral rods 11 and 12. The spring 10 bears against a pin 13 fixed on a rocking pawl 14 pivoted at 15 to a stationary part of the device. A second pin 16 fixed to the pawl 14 supports the end of the contact spring 4 which constantly tends to rock the pawl 14 against the action of the spring 10. The pin 16 is made of electrically nonconductive material. The angular movement of the rocking pawl 14 is limited by two fixed pins 17 and 18.

The pawl 14 is formed with two diametrically opposed arms radiating from its pivot point. Each arm is terminated by an edge arranged to be retained at the proper moment in a hook of a detent member 19 or 20 which detent members are constantly urged toward the pawl 14 by springs 21 and 22, respectively.

The detents 19 and 20 are moved against the action of their springs by means of the rods 11 and 12 respectively carried by the armature 5.

The device as above described in detail, operates in the following manner:

Assuming the parts to occupy the position shown in the drawing, the action of spring 10 is arranged to be greater than that of spring 4 so that the pawl 14 is pressed against the pin 17 in which position the contact spring 4 is maintained in a raised position so as to break the circuit 2. According as the ratchet wheel 9 is turned under the influence of the spring 7, the armature 5 and the pawl 8, the movement of the armature 5 away from the electro-magnet cores 1' raises the spring 10 from the pin 13 so that after a given movement it no longer exerts pressure on or contacts with the pin 13. At this moment the contact spring 4 rocks the pawl 14 until the end of the upper arm of the pawl 14 becomes engaged in the hook of the detent 19. At this time the circuit 2 is not yet closed, but on the contrary, the rod 12 is moved away from the detent 20 which under the action of its spring 22 presses against the end of the lower arm of the pawl 14. The armature 5

continues its upward movement so that the rod 11 finally presses against the detent 19 to raise the same and disconnect the upper arm of the pawl 14 from the detent 19 whereupon under the action of the spring contact 4 the pawl 14 is quickly and brusquely rocked into the position shown in the figure by dot and dash lines to a position limited by the stop pin 18. This last movement permits the spring contact 4 to instantaneously close the circuit 2.

As a result of the above operation the armature 5 is quickly attracted by the electro-magnet. The attraction of the armature by the magnet results in the detent 19 being pressed against the upper arm of the pawl 14, while the spring 10 is pressed against the pin 13 and tends to rock the pawl 14 back into its full line position as shown in the drawing, against the action of the spring contact 4. But the return movement of the pawl 14 is not possible at this moment since the end of the lower arm of the pawl 14, is retained by the hooked end of the detent 20. As a result of this condition the spring 10 is tensioned more and more up to the moment when the rod 12 presses against the detent 20 and moves it downwardly so as to release the pawl 14 and thus permit the spring 10 to act to rock the pawl 14 and brusquely bring it back to its full line position. This movement of the pawl 14 through the pin 16 raises the spring contact 4 and instantaneously opens the circuit 2.

During the movement of the armature 5 under the attraction of the electro-magnet, the spring pawl 8 has moved backward over the teeth of the ratchet wheel 9 and at the same time the spring 7 has been re-tensioned.

The above cycle of operations is thus automatically repeated at periodic intervals.

Having now described a complete form of my invention, what I claim is:—

1. An electric switch comprising a pair of contacts, one being a spring contact, an actuating member, a spring carried thereby, a rocking lever pivotally supported for limited oscillatory movement between said spring contact and said actuator spring, said spring members normally engaging said lever at opposite ends of its axis of oscillation and each

tending to bias it in opposite directions, the normal position of said rocking lever being such that the spring contact is maintained separated from its cooperating contact member, spring-pressed pawls for normally holding said rocking lever in one or the other of its oscillatory positions, and means carried by said actuating member for alternately releasing said pawls at critical positions of said actuating member in which the actuator spring is or is not effective in overcoming the tension of said spring contact, for permitting oscillatory movement of said rocking lever, instantaneously making or breaking the circuit through release or engagement of said spring contact.

2. An electric switch comprising a pair of contacts, one being a spring contact, an electromagnet in the switch circuit, an armature for said magnet, a spring carried by said armature, a rocking lever pivotally supported for limited oscillatory movement between said spring contact and said armature spring, said spring members normally engaging said lever at opposite sides of its axis of oscillation and each tending to bias it in opposite directions, the normal position of said rocking lever being such that the spring contact is maintained separated from its cooperating contact member, spring-pressed pawls for normally holding said lever in one or the other of its oscillatory positions, and means carried by said armature for alternately releasing said pawls at critical positions of said armature in which the armature spring is or is not effective in overcoming the tension of said spring contact, for permitting oscillation of said rocking lever, instantaneously making or breaking the circuit through release or engagement of said spring contact.

3. An electric switch as claimed in claim 6, in which a spring is provided for normally holding said armature away from said magnet, the movement of said armature in response to said spring being relatively slow compared with its movement due to energization of said magnet.

In testimony whereof I have signed my name to this specification.

FRANCOIS FAVARGER.
